S. Cump's Device for Labeling
Canned Goods

UNITED STATES
PATENT OFFICE
JUN 30 1859

NOTICE.

The Cassava plant, or Tapioca of Brazil, is a shrub about six or eight feet in height, with a very large, white, fleshy, tuberous root, which often weighs thirty pounds. It is cultivated extensively in tropical America for the sake of its root, which is much employed as an article of food, being nutritious, and, at the same time, easy of digestion, and destitute of all irritating properties. Tapioca-Farina forms an excellent diet for the sick and convalescent. It is prepared for use by boiling in milk or water. Lemon-juice and sugar will usually be found grateful additions; and in low state of disease, or cases of debility, it may be advantageously impregnated with wine and nutmeg, or other flavoring.

DIRECTIONS.

Tapioca-Farina, or Cassava Pudding. — Soak one-half pound in a pint of milk. Boil a quart of milk, and, when boiling, add the soaked Cassava, a small piece of butter, six white-spoons of sugar, and a little salt. Boil three or four minutes. When cool, add four eggs, well beaten, and bake in an oven.

French Pudding. — One-quarter pound Tapioca, one-half pound flour, one-half pound sugar, one-half pound butter, white sugar, flour, eggs, and some vanilla. To form the eggs, one-half pint milk, two-yolks of eggs, one-quarter pound butter, and a little sugar.

Griddle Cakes. — Use the Cassava half and half hour to thicken the batter. They are delicious.

Soup. — Take two ounces of Cassava; boil fifteen minutes in two quarts of water; add four table-spoonsfuls extract of beef's soup, butter, and season to taste.

This article can be used by any person, boiled in milk, creaming, and flavoring, with sugar, or any other flavoring.

THIS TAPIOCA-FARINA.

Recommends itself for its Perfect Purity, Taste, and Hygienic Qualities, and is a great, agreeable, and interesting article for house-keeping, where persons have been restricted in their diet, and other constitutional infirm, and other failing health.

Persons who have appreciated the superiority of this article, and who desire to use it, can obtain it at the following dealers: Delaney Brothers, New York; and at all the principal grocery and druggist stores.

This new material when prepared, is a white, solid, or black, or black-brown, and is easily digestible.

United States Patent Office.

SAMUEL CRUMP, OF NEW YORK, N. Y., ASSIGNOR TO E. C. HAZARD, OF THE SAME PLACE.

Design No. 3,073, dated June 30, 1868.

DESIGN FOR A LABEL.

The Schedule referred to in these Letters Patent and making part of the same.

TO ALL WHOM IT MAY CONCERN:

Be it known that I, SAMUEL CRUMP, of the city, county, and State of New York, have invented a new Design for Labels; and I do hereby declare that the following is a full, clear, and exact description of the same, reference being had to the accompanying drawing, making a portion of this specification, which represents—

A label made according to my design.

In the drawing are shown the stem *c*, branches *d*, leaves *e*, flowers *f*, and fruit *g* of the cassava-plant, the stem *c* terminating, at its lower end, in bulbous figures, *m*, representing the roots of such plant, the several parts mentioned together constituting the figure of the cassava-plant entire, the upper portion of the stem, with the branches, leaves, flowers, and fruit, being represented within the circle *a*, and the lower portion, with the bulbous roots within the smaller circle *b*, the whole of my design being embraced within the black lines on the drawing.

What I claim as my invention, and desire to secure by Letters Patent, is—

The design and configuration of a trade-mark, as herein shown and described.

SAM'L CRUMP.
